BY *W. B. Hoppe*

ATTYS.

UNITED STATES PATENT OFFICE.

WILLIAM B. HOPPE, OF SAN FRANCISCO, CALIFORNIA.

NECKTIE APPLIANCE.

Application filed October 8, 1920. Serial No. 415,598.

To all whom it may concern:

Be it known that I, WILLIAM BERNHARD HOPPE, a citizen of the United States, residing at 318 Fair Oaks St., San Francisco, in the county of San Francisco and State of California, have invented a new and useful Necktie Appliance, of which the following is a specification.

The present invention relates to improvements in necktie clasps and has particular reference to a device of this character which will make it unnecessary to form a knot in the tie, will provide a unique and fanciful decoration and permit of quick and efficacious arrangement of a tie so that the same has the appearance of being knotted.

One of the objects of the invention is to provide a simple and inexpensive clasp of the character described which comprises a decorative body portion having an opening therein to reveal a portion of the tie, in such manner that the same will appear to be knotted, the said device including a band with an opening in one side to facilitate an efficacious mounting of the device upon the tie, being further provided with novel and effective means for holding it in place between the turndown folds of a collar.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawings:

Fig. 1 is a front elevation of the device of my invention showing it as it would appear when in use.

Fig. 2 is a rear elevation of the clasp.

Fig. 3 is a vertical longitudinal section.

Fig. 4 is a top plan view of a blank of which the device is formed, showing it as it would appear before being bent into shape.

Fig. 5 is a cross sectional view on line 5—5 of Fig. 1.

Referring to the embodiment of the invention as shown in the accompanying drawings in which similar reference numerals refer to similar parts thruout the

several views, 1 designates the body portion of the clasp of my invention, which body portion is provided with an opening 2 therein, preferably of such a shape that portions of a necktie 3 revealed through the opening will simulate a necktie knot of the four-in-hand type. However, the opening may be of various shapes as desired. At the lower end of the body portions is formed a band-like member 4 open on its rear side as at 5. Extending from opposite sides of the bent portion are enlarged portions or flanges 6 cut so as to have decorative curving lines and arranged so as to embrace the side edges 7 of the tie so as to conceal the same, the upper portion of the body being of less width than the sides or flanges 6. At the upper end of the body portion there is a downwardly and rearwardly projecting prong 7, whereby the same may be caught in the necktie so as to hold the clasp in place. As shown in Fig. 4, the device may be stamped from a single blank of metal and then bent into a fancy form as shown in Figs. 1, 2, 3 and 5. The metal of which the device is formed may be gold, silver, platinum, or any other material and preferably is engraved in decorative figures so that the device will be highly ornamental as to appearance.

To apply the clasp, the necktie or cravat is placed in the collar in the customary manner and the ends projecting out of the collar are folded over one another or overlapped as often as required to form a knot or is otherwise overlapped so that a knot may be simulated. After this is done the hanging ends of the tie are forced into the band 4 thru the opening 5 in the rear of the band, so that the tie is completely surrounded by the band with the flanges or side portions 6 embracing the side edges of the tie. The device is then forced upwardly so as to embrace the wrapped or folded portions in the space between the folds of the collar so that such folded or wrapped portion will be revealed within the opening 2 and the flanges or sides 6 will engage the opposite sides of the folded or wrapped portion. To hold the device in place the prong 7 is caused to engage into the folded or wrapped portion.

To remove the clasp it is only necessary to lift upwardly so as to disengage the prong and then pull the ends of the tie out thru the opening 5. By smoothing out the

exposed portion of the tie within the confines of the opening 2, a neat knot will be simulated, the effect being as though the ordinary knot were surrounded by the frame of the general outline of the knot.

Although I prefer to use the device without tying the ordinary knot, it can be equally well used in connection with a tie in which such knot has already been formed, 10 although the same effect may be obtained as to appearance of the tie without forming the ordinary knot. One of the principal features of the invention is the formation thereof which enhances the appearance 15 of the tie and at the same time permits of an easy and efficacious attachment and removal of the clasp relative to the tie.

I claim:

1. A neck-tie appliance comprising a body 20 portion having an opening therein thru which a portion of a necktie disposed behind the body portion is revealed with the appearance of a four-in-hand knot and a band at the lower end of the body portion 25 and having an opening in the rear side thereof to permit of the insertion of the necktie into the band.

2. A neck-tie appliance comprising a body portion having an opening therein thru 30 which a portion of a necktie disposed be-

hind the body portion is revealed with the appearance of a four-in-hand knot, a split band at the lower end of the body portion adapted to receive the necktie and a downwardly and rearwardly projecting prong 35 on the upper edge of the body portion.

3. A neck-tie appliance comprising a body portion adapted to lie over the necktie adjacent to the folds of a collar and having an opening therein thru which a portion of 40 the tie is revealed and a band-like portion on the lower extremity of said body, which band is open on one side and adapted to nearly surround a necktie, said body portion being tapered from its upper to its 45 lower end.

4. A neck-tie appliance comprising a body portion of the general appearance of a four-in-hand knot and adapted to overlie a necktie, said body portion having an opening 50 therein of the same general appearance as a four-in-hand knot, thru which the tie is revealed in the appearance of a knot, portions on said body portion extending rearwardly therefrom and adapted to embrace 55 the tie and a downwardly and rearwardly projecting prong on the upper end of said portion adapted to extend into the tie to hold the body portion in place.

WILLIAM B. HOPPE.
